UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

CRUSHING-MILL.

1,122,552.

Specification of Letters Patent. Patented Dec. 29, 1914.

Application filed November 10, 1911. Serial No. 659,561.

To all whom it may concern:

Be it known that I, THOMAS J. STURTEVANT, a citizen of the United States, residing at Wellesley, in the county of Norfolk and State of Massachusetts, have invented or discovered certain new and useful Improvements in Crushing-Mills, of which the following is a specification, reference being had therein to the accompanying drawings.

10 This invention relates to that class of ring-roll crushing mills, such, for example, as are shown in U. S. Patents Nos. 906,829 and 995,580; and the present improvement has for its object to provide a mill, of the 15 class referred to, which will have a much greater crushing capacity, in proportion to its weight and cost and also in proportion to the power required to drive it, which will occupy much less space in proportion to its 20 capacity, and which will be more evenly balanced, so that it will run smoothly and will be subject to less strain, than the mills shown and described in said patents.

The present improved mill comprises a 25 base provided with suitable standards in which are journaled a single rotating shaft to the opposite ends of which are mounted carriers for rotating anvil rings inclosed in casings at the opposite ends of the said base. 30 Coöoperating with each of the anvil rings referred to are spring-pressed crushing rolls which are mounted on heads or doors constituting casing parts and closing the ends of the two casings referred to. The material 35 to be crushed is supplied to the anvil rings from suitable hoppers mounted on the casing parts, and from which hoppers extend feed spouts to convey the material to be crushed to the said anvil rings. It will 40 thus be understood that the present improvement provides a duplex ring-roll crushing-mill which may be built at a cost very much less than the cost of two mills would be, while providing a mill occupying 45 much less space than would be occupied by two mills of equal capacity. This duplex mill can be driven at considerably less power than would be required to drive two mills of equal capacity. In addition to 50 these advantages the present improvement provides a mill which is evenly balanced, as no single mill could be, in that, when running, the end thrust of one head or anvil ring carrier balances the end thrust of the 55 other head or carrier; and the weight of one head or carrier balances the weight of the other.

In the accompanying drawings Figure 1 is a side view, partly in vertical section, of a mill embodying the present invention, and Fig. 2 is an end view thereof.

Referring to the drawings, 12 denotes the base of the mill which is provided with standards 13, the said base and standards affording a suitable fixed support in which the horizontal driving shaft 14 is journaled. 60 Mounted at each end of the base 12 is a casing 15. Attached to each end of the shaft 14, and housed within the casings 15, is a head or carrier 16, preferably of open-work or spider-form construction, and to each of the said carriers is secured, in any suitable manner, an anvil ring 17 arranged to rotate in a vertical plane. The casings 15 are closed at their ends by doors or 65 heads 18 preferably made in the form of swinging doors hinged on posts 19 mounted on the base 12, this open-door construction being similar to that shown and described in U. S. Patent No. 995,580 hereinbefore referred to. Pivotaly supported on the end heads or doors 18 are a series of crushing roll carriers 20 from which are supported the crushing rolls 21. The crushing roll carriers are provided with bearing pins or 70 stub-shafts 22 on which rotate sleeves 23 to which the said crushing rolls 21 are secured. Any desired number of crushing rolls, from 75 one to three or more, may be employed in coöperation with each anvil ring. In the 70 mill herein shown three crushing rolls are provided to coöperate with each anvil ring. The crushing rolls are yieldingly forced toward the inner face of the anvil rings 17 by means of springs 24 acting on three- 80 armed brackets or spiders 25 attached to said end heads 18 by means of bolts 26 provided with suitable nuts or washers and encircled by the said springs 24. The brackets or spiders 25 are each provided with a central pressure-pin or screw 27 acting on a pressure plate 28 which in turn engages blocks 29 between which and similar blocks 30 on the pivoted crushing roll carriers 20 are preferably interposed anti-friction balls 85 31. By virtue of this construction the pressure of the several springs 24 is evenly distributed to the several crushing roll supports or carriers 20, as in the machine of Patent No. 995,580, hereinbefore referred to. 90

The pressure of the springs 24, to urge the crushing rolls 21 toward the anvil ring 17, may be regulated by adjustment of the screw pressure-pins or bolts 27 in the 5 spiders 25.

Owing to the fact that the crushing rolls 21 are yieldingly supported from the pivoted and spring-pressed roll-carriers 20 the said rolls, when in operation, will be forced 10 inward from the positions shown in Fig. 1 by the material on the anvil rings 17 and will therefore run at an angle to said rings so as to have a scuffing action which contributes largely to the efficiency of the 15 crushing operation. This scuffing action produces more or less end thrust on the shaft 14, and this end thrust is balanced by the duplicated anvil rings and co-operating crushing rolls at the opposite ends of 20 the mill.

The material to be crushed is fed to the anvil-rings from hoppers 32 through suitable feed spouts 33, these parts, as herein shown, being mounted on the swinging end 25 head or doors 18. In the construction herein shown the driving shaft 14 is intended to be driven from a gear wheel 34 secured to said shaft and geared to a power shaft, not shown; but it will be understood that said 30 shaft 14 may be otherwise driven, as from a belt pulley or motor mounted directly thereon.

From the foregoing it will be understood that the present invention provides a duplex 35 ring-roll crushing mill each part of which will have the same crushing capacity as a single ring-roll mill of the same size; while, owing to the fact that the two sets of crushing elements are mounted on a single base 40 and are driven from a single shaft, the improved mill comprises a lesser number of parts and a lesser number of bearings than would be required for two mills; and being of compact construction, will occupy much 45 less space than would be required for two mills of a similar capacity. Also, owing to the fact that the two heads or carriers for the anvil rings are mounted upon a single shaft, it will be evident that the end thrust 50 and the weight of one head or carrier will be balanced by the end thrust and the weight of the other head or carrier. Also the two rings and carriers at the opposite ends of the shaft on which the carriers are 55 mounted serve to balance torsional strain by the double fly-wheel momentum effect afforded thereby, and the shocks in one crushing mill are more or less absorbed in the other so that the mill runs quietly and suff- 60 fers much less wear and tear than a single mill. Also the two parts of the duplex mill may be run as separate mills, so that one may be running while the other may be idle for repairs, in that the hoppers and crush- 65 ing elements of the two parts are separate

and independent. Also when the crushing rolls are supported from swinging end heads, as shown in U. S. Patent No. 995,580, the great weight of one head and the parts mounted thereon will, when said heads are 70 opened, be balanced by the weight of the other, carrying similar parts, this balancing of the weight being due to the fact that said end heads are, in practice, mounted to swing outward in opposite directions on opposite sides of the base 12. It will also be evident that the present improvement will dispense with one set of driving gearing as compared with the driving gearing required for two single mills, thus lessening cost and providing a construction which will require less power, in the operation of the mill, than would be required for two mills of similar capacity; as also diminishing the weight of the mill in proportion to its crushing capacity.

Having thus described my invention I claim and desire to secure by Letters Patent:

1. In a ring roll crushing mill, the combination with a suitable base provided with standards, of a driving shaft journaled in said standards, anvil ring carriers mounted at the opposite ends of said shaft and balancing each other as to weight, anvil rings fixed to said carriers, casings mounted at the opposite ends of said base and serving as housings for said carriers and anvil rings, swinging end heads closing the ends of said casings, pivoted and spring-pressed roll-carriers mounted in said swinging heads, pins or stub-shafts fixed to said spring-pressed roll-carriers, and crushing rolls mounted to rotate on said pins or stub-shafts and co-operating with said anvil rings, said yieldingly-mounted rolls, when in operation, having a scuffing action on said anvil rings and which scuffing action produces more or less end thrust on said shaft, such end thrust being balanced by the duplicated anvil rings and co-operating yieldingly-mounted crushing rolls at the opposite ends of said shaft.

2. In a ring roll crushing mill, the combination with a suitable base provided with standards, of a driving shaft journaled in said standards, anvil ring carriers mounted at the opposite ends of said shaft and balancing each other as to weight, anvil rings fixed to said carriers, casings mounted at the opposite ends of said base and serving as housings for said carriers and anvil rings, swinging end heads closing the ends of said casings, said end heads being mounted to swing outward on opposite sides of said base so as to balance each other when open, pivoted and spring-pressed roll-carriers mounted in said swinging heads, pins or stub-shafts fixed to said spring-pressed roll-carriers, and crushing rolls mounted to rotate on said pins or stub-shafts and co-operating with said anvil rings, said yieldingly-

mounted rolls, when in operation, having a scuffing action on said anvil rings and which scuffing action produces more or less end thrust on said shaft, such end thrust being balanced by the duplicated anvil rings and coöperating yieldingly-mounted crushing rolls at the opposite ends of said shaft.

3. In a ring-roll crushing mill, the combination with a base provided with standards, 10 of a driving shaft journaled in said standards, casing parts mounted at the opposite ends of said base, anvil-ring carriers secured to the opposite ends of said shaft and balancing each other as to 15 weight, an anvil ring attached to each of said carriers, a plurality of spring-pressed crushing rolls coöperating with each of said anvil rings, heads for closing the ends of said casing parts, bearing pins or stub- 20 shafts supported on said heads and on which

pins or shafts the said crushing rolls are rotatably mounted, pivoted crushing-roll carriers in which the said pins or shafts are mounted, springs for yieldingly pressing the said crushing rolls toward the said anvil 25 rings, and a single bracket or spider at each end of the mill and through which and suitable coöperating parts the pressure of a set of said springs is evenly distributed to a set of crushing-roll carriers; the conjoint action 30 of said rings and rolls producing end thrust on said shaft, and which end thrust is balanced by the duplicated crushing mechanisms at the opposite ends of said shaft.

In testimony whereof I affix my signature, 35 in presence of two witnesses.
